UNITED STATES PATENT OFFICE.

JUSTIN O. SCHWARZ, OF NEW YORK, N. Y., AND GUSTAV BJORKLUND, OF WEST NEW YORK, NEW JERSEY.

PEDAL MECHANISM FOR PNEUMATIC DEVICES.

1,306,081.

Specification of Letters Patent. Patented June 10, 1919.

Application filed October 6, 1917. Serial No. 195,191.

To all whom it may concern:

Be it known that we, JUSTIN O. SCHWARZ, a citizen of the United States, and GUSTAV BJORKLUND, a subject of the King of Sweden, residing at New York city, N. Y., and West New York, N. J., respectively, have invented certain new and useful Improvements in Pedal Mechanism for Pneumatic Devices, of which the following is a specification, reference being had therein to the accompanying drawing.

Our invention relates to improvements in pedal mechanisms for pneumatic devices such as musical instruments, and has particular reference to and is illustrated in the accompanying drawing in its application to a folding pedal for a player-piano.

Referring to said drawing indicated as Figure 1, 2 indicates the bottom of a cabinet or piano upon which the bracket or casting 3 is secured as shown. At each side of this bracket or casting is secured a substantially Y-shaped member 4 pivoted at 5 to the overhanging flange 3' of the bracket 3 and at 6 to the lever 7 pivotally connected to the foot-board 8 at 9. 10 indicates another lever somewhat L-shaped which is also pivoted to the end of the flange 3' at 11 as shown and at its outer end secured to the toe-plate 12 pivotally mounted at 13 and provided with toes 14—14', said pivotal bearing 13 being secured to the base of the pedal-boards 8—8' as shown.

The other leg of the Y-shaped member 4 is pivotally secured at 15 to the rod 16 which in turn is pivoted at the other end at 17 to the lever 18, one end of which is pivotally secured at 19 to the bracket 20 upon the underside of the piano 21, the other free end of the bracket 18 being pivotally connected to the lever 23 which in turn is pivotally secured at 24 to the movable portion of the bellows 25 being suitably secured thereupon by the bracket 26, it being understood that all of said parts are duplicated upon the other side of the pedal mechanism for operating the bellows 25.

From the foregoing it will be seen that the front of the foot-pedals are supported by the toes 14—14' when in use, and as the foot-board 8 is operated the Y-shaped lever 4 is oscillated upon the pivotal bearing 5 thereby transmitting the thrust of the foot-board 8 through the connecting members 7, 4 and 16 and bracket and rod 18 and 23 to the bel-

lows 25 for pneumatically operating the piano, the same operation taking place from the foot-board 8' to the bellows 25' at the other side of the mechanism. When it is desired to fold the pedal mechanism out of the way, the toe-bar 12 may be lifted upwardly and backwardly, thus bringing the toe-piece to the top and inverting the position of the foot-boards which will thereupon remain in a vertical position behind the front of the piano indicated by the reference character 26, thus providing a simple, compact, durable and easily operable pedal mechanism which can be quickly and conveniently dropped out of the front of a piano for use or folded back into the same when not desired for automatic playing.

The particular folding pedal mechanism herein shown and described has been illustrated in its application more particularly to a baby grand piano, although it will be readily understood that the same is susceptible of application to an upright piano or other form of pneumatic instrument, and in fact various modifications may be made in the construction and arrangement of parts without departing from the spirit of the invention as claimed.

We claim:

1. In combination with a folding pedal mechanism, a base bracket therefor, and at each side thereof a substantially Y-shaped pivoted member, one leg of which is pivotally secured to said base bracket and the other leg of which is pivotally connected with a pneumatic, the stem of said Y-shaped member being pivotally secured by a lever to a pedal-board at one end, and the other end of said pedal-board being connected by a lever to said base support.

2. In combination with a folding pedal mechanism, a base bracket therefor, and at each side thereof a substantially Y-shaped pivoted member, one leg of which is pivotally secured to said base bracket and the other leg of which is pivotally connected with a pneumatic, the stem of said Y-shaped member being pivotally secured by a lever to a pedal-board at one end, and the other end of said pedal-board being connected by a lever to said base support, said lever connecting said base support and said pedal-board having interposed therebetween a toe support for said pedal-board.

3. In combination with a folding pedal

mechanism, a base bracket therefor, and at each side thereof a substantially Y-shaped pivoted member, one leg of which is pivotally secured to said base bracket and the other leg of which is pivotally connected with a pneumatic, the stem of said Y-shaped member being pivotally secured by a lever to a pedal-board at one end, and the other end of said pedal-board being pivotally connected by a lever to said base support, said pivotal connection between said pneumatic and one of the legs of said Y-shaped member comprising a lever pivotally connected to said pneumatic and a lever pivotally con-

nected to one of the legs of said Y-shaped member, and a bracket between said levers pivotally connected thereto and to a fixed portion of the instrument upon which said pedal mechanism is to be applied. 15

In testimony whereof we hereunto affix 20 our signatures in the presence of two witnesses.

JUSTIN O. SCHWARZ.
GUSTAV BJORKLUND.
